UNITED STATES PATENT OFFICE.

HENRY SPENCER LAWSON, OF JERSEY CITY, NEW JERSEY, ASSIGNOR TO
THE PANTASOTE LEATHER COMPANY, OF PASSAIC, NEW JERSEY.

DESIGN FOR TEXTILE FABRIC.

SPECIFICATION forming part of Design No. 28,825, dated June 7, 1898.

Application filed April 25, 1898. Serial No. 678,807. Term of patent 7 years.

To all whom it may concern:

Be it known that I, HENRY SPENCER LAWSON, a subject of Her Majesty the Queen of Great Britain, residing at Jersey City, in the county of Hudson and State of New Jersey, have invented and produced a new and original Design for Textile Fabrics, of which the following is a specification, reference being had to the accompanying drawings, forming part thereof.

The drawing is a plan view showing my new design.

As shown in the drawing, the leading or material feature of my design consists of an equilateral four-sided figure A, the sides of

which are of a scalloped or undulating configuration made on a slightly-concave curve, as at B. Each figure contains five dots or small circles arranged cruciform, as at C. At the point of conjunction of a plurality of said figures is a circle D.

Having described my invention, what I claim as new, and desire to secure by Letters Patent, is—

The design for textile fabric as herein shown and described.

H. SPENCER LAWSON.
